UNITED STATES PATENT OFFICE.

WILLIAM WAFER, OF OAK PARK, ILLINOIS.

AUTOMATIC SAFETY-VALVE.

1,071,972.

Specification of Letters Patent.

Patented Sept. 2, 1913.

Application filed December 8, 1912. Serial No. 735,252.

To all whom it may concern:

Be it known that I, WILLIAM WAFER, a citizen of the United States of America, residing at Oak Park, in the county of Cook and State of Illinois, have invented certain new and useful Improvements in Automatic Safety-Valves, of which the following is a specification.

My invention relates to valves for regulating fluid pressure, but more particularly to that class of valves used for automatically relieving any excess of pressure in a steam boiler so as to keep the steam pressure from exceeding a predetermined amount. Such safety valves, when designed to be actuated by the slight excess in steam pressure which may easily occur at brief intervals of time, are commonly known as "pop valves," but have heretofore been limited in their use owing to the complications involved in the timing or adjusting features of such valves and the consequent high cost of the same.

The chief objects of my invention are to provide a pop valve which will be simple and easy of manufacture; which will be easy to clean or repair; and which can readily be adjusted to vary the time interval during which the valve remains open when actuated, thereby varying the amount by which the pressure in the boiler is reduced during the time that the valve was open.

I attain these objects by the construction shown in the accompanying drawings, forming a part of this specification, and in which—

Figure 1 is a side elevation of my valve, with the casing and spring in section; Fig. 2 is a top plan view; Fig. 3 is a vertical sectional view of the valve; Fig. 4 is a horizontal section taken through Fig. 3 along the line 4—4; Fig. 5 is a bottom plan view of the valve proper.

In its preferred form, my invention consists of a body 1, provided at its lower end with a female thread 2, for attaching it to a steam pipe of a locomotive, or other steam boiler. Immediately above the said inner thread 2, and preferably somewhat greater in diameter, is a cylindrical bore 3, formed in the body casting 1, and in which bore 3 the guide for the valve plunger is adapted to reciprocate. This valve plunger consists of a lower guide portion, an upper outlet pipe, and a hollow chamber between the two. The lower guide portion preferably consists

of a plurality of vertical wings 4, arranged radially to the axis of the valve, these wings being turned at their outer edges to conform to the contour of the bore 3 of the body 1 of the valve. Above the upper ends of these wings, the plunger has a beveled face 5, shaped to match a beveled valve seat 6, formed on the body casting 1, around the upper end of the bore 3, thereof, so that the two will form a closure when the plunger is depressed. Above the face 5, and outwardly of the same is a downwardly extending flanged ring 7, which has a lower sharp edge forming a lip 8, which, when the valve is closed, sets upon a beveled seat 9, formed around the upper outer edge of the body 1. Perforations 10, lead from a number of points within this flanged ring 7, to a hollow chamber 11, within the plunger from which chamber 11, a vent pipe 12, leads upward through the top of the valve casing 13. Surrounding this pipe 12, is a spring 14, bearing at its lower end against the disk 15, which, in turn, bears against the top of the valve plunger, and at its upper end against a disk 16. This disk 16, rests against the inner end of a bushing 17, screwed into the top of the valve casing 13, and locked in position by a jamb-nut 18. Near its upper end the vent pipe 12, is provided with a series of perforations 19, and is internally threaded to receive an adjusting screw 20.

Surrounding the part of the body 1, just below the valve seat 6, is an annular trough 21, preferably rounded at its lower end as shown in Fig. 3, the outer edge of the trough being formed by an outer cylindrical portion 22, of the valve casing. This outer portion 22, is connected to the main portion 13, of the valve casing by radial webs 23, and is screwed at its lower end to the body 1, just below the said trough 21.

In addition to the guide wings 4, the plunger also has an added guide portion 24, sliding within the valve casing 13, at its lower end, there being suitable vents 25, in the top of the casing to prevent a compression of air in the casing to hinder the movement of the valve plunger.

When the valve is in use steam passing through the threaded body casting 1, into the bore 3, will circulate freely between the guide wings 4, of the valve plunger and exert an upward pressure upon the plunger, which pressure is resisted by the spring 14.

When the steam pressure exceeds the tension for which the spring is adjusted, by the position of the bushing, it will lift the plunger, thereby allowing steam to issue from the bore 3, of the valve body 1, against the downwardly flanged ring 7, which will direct it downward and outward into the annular trough 21. The latter, in turn, will deflect the steam in an upward direction so that it will pass out between the concentric portions 13 and 22 of the valve casing. Steam will also enter the hollow chamber of the valve plunger through the perforations 10, and will then pass up the vent pipe 12, and out through the small perforations 19. As soon as sufficient steam has escaped from the boiler in this way to relieve the excess of pressure needed to overcome the normal tension of the spring 14, this spring will tend to return the valve plunger to its seated position. In so doing it will compress the steam which is in the chamber 11, the vent pipe 12, and the annular space 26, bounded by the valve face 5, the flanged ring 7, and the upper face of the valve body 1. When thus suddenly compressed the steam inclosed in the passage just mentioned will form a cushion to resist the closure of the valve plunger, thus holding the valve slightly off its seat until the pressure of the said entrapped steam is sufficiently reduced by leakage through the small perforations 19, in the upper end of the vent pipe 12. The length of time required for this leakage to take place is readily controlled by the screw 20, which may be moved to open a larger or smaller number of the perforations 19. If these perforations 19, do not relieve the pressure of the entrapped steam fast enough to allow the valve to close as quickly as desired, they may be supplemented by auxiliary perforations 27, leading from the annular passage 26, as shown by dotted lines in Figs. 3, 4 and 5.

It will be obvious from the above description and accompanying drawings that a valve constructed in accordance with my invention is easy to make and has very few parts; that it can be easily adjusted as to its actuating pressure by moving the bushing 17, and as to its time of pressure-relieving, or the number of pounds of pressure allowed to escape from the boiler after the actuating pressure is overcome, by adjusting the screw 20, to throttle the vent pipe 12, more or less. By suitably setting the screw 20, the time required for the valve to close can easily be lengthened so that the valve will not only relieve the actual excess of boiler pressure required for operating the valve, but will lessen the pressure by one or several pounds below that at which the valve opened. It will also be evident from the drawings that the flanged ring 7, and the annular trough 21 cooperate to deflect the escaping steam in a

substantially vertical direction so that it will have free passage to the air through the space between the portions 13 and 22 of the valve casing.

While I have shown and described my pop-valve in its preferred embodiment, I do not wish to be limited to the precise details disclosed, it being evident, that various modifications may be made in various parts of the device without departing from the spirit of my invention.

Having thus fully described my invention, what I claim as new and desire to secure by Letters Patent is—

1. In a safety pop valve having a valve seat, a reciprocal plunger adapted to form a closure when depressed against the valve seat, and to limit steam when raised from the said valve seat by the pressure of steam upon the plunger, there being a downwardly open annular grooved formation upon the plunger adjacent to its engagement with the valve seat, said plunger also having a chamber formed within the same above said annular groove and connected with the said grooved formation by perforations, and a vent pipe carried by the plunger and connected with the said chamber.

2. In a safety pop valve having a valve seat, a reciprocal plunger adapted to form a closure when depressed against the valve seat, and to limit steam when raised from the said valve seat by the pressure of steam upon the plunger, there being a downwardly open annular grooved formation upon the plunger adjacent to its engagement with the valve seat, said plunger also having a chamber within the same connected with the said grooved formation by perforations, a vent pipe carried by the plunger and connected with the said chamber, and adjustable means carried by said vent pipe for throttling the same.

3. In a safety pop valve for steam boilers having a valve seat, a reciprocable interiorly chambered plunger having an annular grooved formation adjacent to its engagement with the valve seat, and having the interior chamber connected with the said grooved formation by perforations, the said plunger having a throttled vent connected with the said interior chamber, the said grooved formation and chamber being adapted to entrap steam under pressure when the plunger is forced toward the valve seat, and a spring tending to press the plunger into engagement with the valve seat.

4. In a steam safety pop valve having a valve seat, an interiorly chambered plunger adapted to make a closure with the valve seat, there being passages adjacent to the closure for providing a rapid entrance for steam into the said interior chamber, and a passage for providing a slow leakage of steam from the said chamber.

5. In a steam safety pop valve having a valve seat, an interiorly chambered plunger adapted to make a closure with the valve seat, there being passages adjacent to the closure for providing a rapid entrance for steam into the said interior chamber, and an adjustably throttled passage for providing a slow leakage of steam from the said chamber.

In witness whereof, I have hereunto subscribed my name this 30th day of November 1912, in the presence of two subscribing witnesses.

WILLIAM WAFER.
